UNITED STATES PATENT OFFICE.

HARRY DALTON, SR., OF PHILADELPHIA, PENNSYLVANIA.

TANK CARBURETOR.

Application filed May 21, 1921. Serial No. 471,375.

To all whom it may concern:

Be it known that I, HARRY DALTON, Sr., a citizen of the United States, residing at Philadelphia, in the county of Philadelphia and State of Pennsylvania, have invented new and useful Improvements in a Tank Carburetor, of which the following is a specification.

My invention relates to new and useful improvements in a tank carburetor, and method of producing carbureted fuel for internal combustion engines, and has for its object to provide for carbureting a volatile fluid contained within a suitable storage tank making it unnecessary to use separate storage tanks and carburetors.

A further object of the invention is to vaporize the volatile fluid in such manner as to prevent undue separation of the lighter elements from the heavier elements thereof by utilizing a series of wicks for elevating the fluid and exposing the same upon fibrous air swept surfaces.

A further object of the invention is to provide means for properly directing the air drawn to and from the tank by the action of the engine so that said air in its passage through the tank will sweep all of the liquid exposing surfaces uniformly.

A further object of the invention is to provide for heating the air in its passage to the tank and also to heat the air admitted to the fuel supply pipe prior to entering the manifold of the engine and to give a swirling motion to said air.

A still further object of the invention is to provide for carrying out the above named objects in a simple and effective manner.

With these and other objects in view, this invention consists in the details of construction and combination of elements herein-after set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a diagrammatical view showing the relation of the tank, engine and connections therefor.

Fig. 2, is a plan view of the tank, the

cover being removed and one of the channelways partly broken away.

Fig. 3, is a side elevation of the tank partly broken away to clearly show the location of the channelway therein.

Fig. 4, is an enlarged perspective of one of the channelways.

Fig. 5, is a perspective on a reduced scale of the series of channelways in position relative to each other.

Fig. 6, is an end view of the tank partly broken away to show the relative position of the channelways therein.

Fig. 7, is an enlarged end view of one of the channelways having its series of wicks secured therein.

Fig. 8, is an enlarged perspective of a portion of one of the channelways showing the wicks secured therein.

Fig. 9, is an enlarged central section of a portion of the secondary intake showing the spiral in the interior thereof.

Fig. 10, is an enlarged section of the relief valve showing the interior construction thereof.

Fig. 11, is an enlarged section of the vacuum regulating valve.

Fig. 12, is an enlarged section of the throttle valve.

In carrying out my invention as here embodied, 1 represents the supply tank which may be of any desired shape or size and is intended to carry a supply of volatile liquid such as gasolene or kerosene which may be introduced thereto through the hopper or funnel 2 so positioned as to prevent the over filling of the tank. Within the tank and spaced at a proper distance from the top thereof are two shelves 3 one at each end of the tank. These shelves act as supports for channelways or wick holders.

4 represent the wick holders which are in the form of channelways, each consisting of a top section 5, two sides 6 bent at right angles to the top section and end flanges 7 in which latter are formed a number of holes 8.

9 represent the wicks which are suspended from rods 10, the ends of the latter being secured in the holes 9, said rods acting as spacers for the wicks at the top thereof while a series of strips 11 of wood or other suitable material serve as spacers for said wicks at a certain distance below. These

strips 11 are secured in place by the wires 12 which pass through the wicks and strips, as shown in Fig. 7, and extend crosswise the entire width of the wicks. Thus it will be seen that each holder carrying a series of wicks may be placed in the tank, the ends thereof resting upon the shelves 3, suspending the lower portion of the wicks within the tank below the shelves, and when the several holders are so placed the strips 11 will act as a baffle dividing the tank horizontally into two compartments A and B, the former for containing the volatile liquid and the latter for the formation of the carbureted fuel mixture. This baffle also serves to prevent the sloshing of the volatile liquid into the compartment B when the device is used on automobiles.

While there may be any desired number of wick holders I have here shown but three, each of which has its sides cutaway to form air passages 13 and 14, said cutaway portions being at opposite ends of the holder and on opposite sides thereof, thus when these holders are properly placed within the compartment B a to and fro passage is provided for the flow of the air through said compartment.

15 represents the inlet for air to the compartment B which is so placed relative to the wick holders when the latter are positioned in the tank that the incoming air will enter one end of one of the channelways or wick holders and flowing therethrough pass to the next channelway through the cutaway portion 13 of one channelway and the cutaway portion 14 of the adjacent channelway, then backward through this adjacent channelway and through the opposite cutaway portions to the next adjacent channelway and again forward through this last named channelway to the outlet 16, as indicated by the arrows in Fig. 5. As this air passes through the channelways it will impinge upon and sweep the surfaces of the upper portions of the wicks 9 which are so spaced in said channelways as to cause said air to pass therebetween, thus evaporating the volatile liquid exposed upon said surfaces and thereby becoming thoroughly saturated with the vapor and forming the carbureted fuel mixture for combustion in the engine.

The outlet 16 leads into the fuel supply pipe 17 by which the gasolene fuel is conveyed to the manifold 18 of the engine 19, and in this pipe at any suitable point is located a throttle valve 20, which may be of any suitable construction, here shown of the butterfly type. Since it is highly important that the air entering the compartment B shall be in condition to rapidly evaporate and absorb the volatile liquid from the exposed surfaces of the wicks, I connect the inlet 15 with an intake pipe 21 a portion of which is coiled about the engine

exhaust 22 as shown at 23, so that the incoming air will be heated. The carbureting of the inflowing air in this system tends to produce a highly enriched fuel, and while this is advantageous, it is desirable in the operation of internal combustion engines, especially for automobile vehicles to be able to vary the richness of said fuel in its passage to the engine, therefore I provide a secondary intake 24 leading into the intake 17 between the throttle valve and the manifold at an angle and in this secondary intake is located a control valve 25 by which the amount of air admitted through this secondary intake may be varied, said valve may be operated by any suitable rod or other mechanism terminating in easy reach of the engine driver. In order that the air passing to the intake 17 through the secondary intake 24 may be heated to prevent the chilling of the gaseous fluid I connect the pipe 26 with said secondary intake and so dispose a portion thereof relative to the exhaust or some other heated portion of the engine as to heat the air passing therethrough, the arrangement here shown being the coil 27 placed around the exhaust 22.

I have found in practice that better results are obtained when the air passing through the intake 24 is given a swirling motion and I therefore position a spiral 28 in this intake so that as the air passes therethrough it will be given a spiral motion and thus when commingling with the fluid passing to the engine through the intake 17 will tend more thoroughly to mix therewith.

In order that the air flowing to the tank through the intake pipe 21 may be controlled, I locate a valve 30 of any suitable design here shown as a butterfly valve in said pipe and carry a rod or connection 31 therefrom within easy reach of the engine attendant and as the closing or partly closing of this valve will tend to create a partial vacuum within the tank, I provide a relief valve 32 of any suitable construction which will prevent the formation of an undue degree of vacuum in the tank.

By the arrangement of wicks as herein described it has been found that the raising of the volatile liquid from the compartment A to the compartment B has little or no tendency to separate the lighter from the heavier portions of said fluid and therefore the entire contents of the tank will be raised and vaporized without leaving behind the heavier component parts of said fluid, and by this system the numerous disadvantages attendant upon the use of the separate carburetor are entirely overcome.

While I have here shown one embodiment of my invention it is obvious that it may be embodied in various forms and the construction of the several parts thereof may be widely varied without departing from the

spirit of my invention and I therefore do not wish to be understood as limiting myself to the exact details of construction here shown and described as these may be varied within 5 the limits of the appended claims

Having thus fully described my invention, what I claim as new and useful is:—

1. In a device of the character described, a supply tank, a plurality of channels positioned in the upper portion of the tank, a series of wicks suspended from the channels, said wicks being spaced apart, a baffle through which said wicks pass, said baffle dividing the tank into an upper and lower 10 compartment, and means for causing a current of air to flow through the channels whereby the surfaces of the wicks above the baffle will be swept by said air.

2. In a device of the character described, 20 a supply tank, two shelves secured within said tank, wick holders in the form of channelways supported by said shelves, a series of wicks having their upper portions secured within each of said holders, said 25 wicks projecting downward to the bottom of the tank and being spaced apart, a series of strips interposed between the wicks forming a baffle to divide the tank into an upper and lower compartment, and means 30 for causing a current of air to flow through the channelways between the upper portion of the wicks.

3. In combination with a supply tank for internal combustion engines, a series of 35 channelways located within the upper portion of the tank and placed side by side, cutaway portions in the side walls of the channelways for providing air passages from one channelway to another, a series

of rods secured in each of the channelways, 40 a series of wicks suspended from said rods, spacing strips secured between the wicks in such manner as to form a baffle for dividing the tank into an upper and lower compartment, and means for causing air 45 to flow through the channelways.

4. In a carburetor, the combination with a supply tank having an inlet and an outlet, of a plurality of channelways located in parallelism within the upper portion of 50 the tank and in inverted positions, the side walls of said channelways having cutaway portions adjacent opposite ends, the cutaway portions of one channelway registering with those in adjacent channelways to 55 provide a circuitous passageway and a series of wicks mounted within each of the channelways and hanging below the same.

5. In a device of the character stated, 60 the combination of a supply tank, two shelves within the tank at opposite ends thereof, a plurality of inverted channel wick holders closed at their ends and supported by said shelves, each of said channelways communicating with adjacent channelways at opposite ends to form a circuitous air passageway above the fuel level of the tank, wicks suspended within said channelways and hanging below the fuel level and 65 strips located between the wicks and to which the latter are secured, said strips being located adjacent the channelways and dividing the interior of the tank into two compartments.

In testimony whereof, I have hereunto 70 affixed my signature:

HARRY DALTON, Sr.
